UNITED STATES PATENT OFFICE.

ERNEST A. HOUCHEIN AND ANTHONY HUBER, OF BROOKLYN, NEW YORK.

SOAP-FRAME.

SPECIFICATION forming part of Letters Patent No. 740,438, dated October 6, 1903.

Application filed March 22, 1902. Serial No. 99,505. (No model.)

To all whom it may concern:

Be it known that we, ERNEST A. HOUCHEIN and ANTHONY HUBER, citizens of the United States, residing at Brooklyn, in the county 5 of Kings and State of New York, have invented certain new and useful Improvements in the Construction of Soap-Frames, of which the following is a specification.

Our invention relates to improvements in soap-frames. As a preliminary statement it may be said for general convenience in an understanding of our invention that a soap-frame of the class described consists in the main of a platform upon which rests the cake 15 or mixture of soap and four upright movable sides, which besides being fastened tightly together must also be held or fastened tightly in contiguity with the said platform, each one of the said sides being situated rectangularly 20 to its contiguous fellow side and the whole apparatus being on wheels for convenience in moving.

The objects of our invention are, first, to provide a means of fastening the movable upper 25 right sides of the said soap-frame in a manner which will insure the utmost facility in placing them in their fastened position ready to receive the mixture and also to render the removal of the said sides (so removed to be 30 used upon another base or platform of the usual construction to mold a second supply of soap) performable with ease and despatch; second, to provide a means of moving and guiding the said soap-frame, (with or without 35 its assigned load,) which will be adjustable according to the weight of the apparatus and the strength and height of the person; third, to provide a firm support for the separate distinct pieces comprising the said platform of 40 the soap-frame; fourth, to provide a means of holding the said platform in rigid contiguity with the above-mentioned four upright sides. We attain these objects by the mechanism illustrated in the accompanying drawings, in which—

Figure 1 is a side elevation of the entire soap-frame. Fig. 2 is an end elevation of the entire machine with part of the platform broken away. Fig. 3 is a side elevation of 45 the pivot-truck with the handle broken away, by means of which we raise and guide the frame. Fig. 4 is a bottom view of the plate

used in conjunction with the adjustable screw of the pivot-truck. Fig. 5 is a top view of one of the ends of the soap-frame, showing one of the wooden ends and two of the iron sides broken off and also one of our fastenings in its open or unfastened state. Fig. 6 is a view of the same end, showing one of the two wooden sides or ends, the same two iron sides, 60 and the fastening in its closed or fastened state. Fig. 7 is an end view of the base or platform of the frame, said platform being broken away in order to show a second one of our fastenings in its open or unfastened 65 form. Fig. 8 is same view as Fig. 7, showing the fastening in its closed or fastened form. Fig. 9 is a sectional view taken along the line indicated by the arrows in Fig. 1. Fig. 10 is a view of the pivot-truck in operation raising the front wheels from the floor 70 ready to be moved.

Like numbers or letters refer to like parts throughout the accompanying drawings.

The platform of the soap-frame is represented by 1, said platform being composed of three distinct pieces—namely, a' a^2 a^3 , in Fig. 7. The wooden upright 2, with its mate 2 on the opposite end, and an iron upright 3 on either side of said 2, fastened tightly together, 80 form the four-sided receptacle into which the mixture is to be placed, with the platform 1 as a bottom for the said receptacle or vessel.

We will now proceed to explain the manner in which we fasten together the various 85 contiguous parts, so that extreme simplicity, efficiency, and despatch in handling may be attained.

The upright ends may be set down into a hollow formed in the platform 1, as at B', 90 Figs. 1, 7, and 8. A metal piece 4, bent so as to form a toe, is fastened upon the front of 2, as at B², Fig. 9. The toe of 4 is taken into the eyebolt 5, the threaded end of which is let down through the platform 1 and also through 95 the plate 6, where a nut 5' is placed on the end of 5 and tightened, thereby rigidly holding down 2 to the platform 1.

It has been previously stated that the platform 1 is formed of three pieces. The reason: 100 when the iron sides 3 are let down into 1 to the same depth as 2 the insides of 3 are brought against the sides of the part of 1 called A², while the outsides are next to the parts of 1-

called A' and A³. This will be plainly seen by reference to Figs. 7 and 8. Figs. 7 and 8 are also particularly adapted to an explanation of the mechanical operation of the 5 eccentrically-formed lever 7 and its contingent parts. A rod 8, running through A', A², and A³, is threaded at C' and swelled at the other end C² and is connected by a pin 7' with 7 at C², while the end C' is fitted with a 10 nut 8' and a washer a a. The wood of the platform is cut away where the ends of the rod 8 emerge, so that the nut at C' and the eccentric at C² may not project beyond the outer edge of 1. As will be readily perceived, the 15 throwing into commission of the eccentric 7, as in Fig. 8, will strain the irons 3 between A' and A² and between A² and A³, thereby rendering the platform 1 perfectly tight to any flow of the mixture. The washers are 20 placed upon this rod to prevent the nut or eccentric from cutting into the wood and to provide a firm backing for the said members. The nut upon the threaded end of 8 renders the amount of force required easily adjust- 25 able by a simple turn of the nut 8'.

Referring to Figs. 5 and 6, the apparatus X, shown fastened to 2, as at D', Fig. 2, may be located at any desired height, and it is purposed to provide an upper fastening to 30 bind together the sides 3 and 4. When the lever 9 is thrown into commission, as at Fig. 6, the round rod 10, formed with a bent toe 10', pulls the hooked connection 11 toward the center of the frame, thereby compressing 35 the iron sides 3 against the upright 2, thus rendering the higher parts of the frame as liquid-tight as the bottom. This lever is made adjustable by means of the thread at D², maintaining the adjustment made by 40 means of the jam-nut D³, as will be readily understood. There is yet another way by which the fastening of the sides 3 and 4 at the positions occupied by apparatus X may be accomplished. Fig. 11 explains the mechanism, in which the parts Z and W are rods 45 bent to the shape shown and embracing the frame in a manner similar to that shown by apparatus X. On one end of each of the rods Z and W is cut a thread Z' and W', said 50 thread being right hand on one rod and left hand on the other, both screwing into a member T, fitted with right and left hand threads, suiting the threads on the rods Z and W. It will be readily seen that by the simple turning 55 of the member T in one direction or its opposite while the rods Z and W are secured against revolving with the movement of the member T the said rods Z and W will close on or open from the sides 3, thereby fastening or unfastening the said sides 3 in their 60 position, according to the direction of the movement of the member T. This apparatus we call "apparatus V." There may be any number of the connection 7 and its contingent parts deemed necessary and also any 65 number of the apparatus X and V used in conjunction with our invention.

Returning to Fig. 9, having explained the use of the three pieces composing the platform, it is obvious that the rod 8, Figs. 7 and 8, will have a tendency to support the parts A' and A³. Such support not being sufficient, we have provided the plate 6 with enough length to extend underneath the said parts A' and A³, thus insuring a firm, certain, and 75 helpful support, Fig. 9. This plate 6, besides being secured by the eyebolt 5 and the nut 5', may be fastened upon the bottom of said A² by means of screws inserted through the holes E', Fig. 4, thereby preventing the plate 80 6 from any movement whatever upon the bottom of the platform 1. This plate is provided with a series of depressions E², into which may take the head of a heavy screw 13, situated upon a bearing, Fig. 3, said bearing being called 15 and the pivot-truck in general being called Y. The relative positions of the plate and the screw 13 when in action may be plainly seen at F', Fig. 10. The lowering of the handle 14 will raise 13 into any convenient depression E², and a continuance of the act of lowering 14 will raise the front wheels of the platform 1 from the floor, the weight of 1 being supported upon the pivot-truck Y and the rear wheels of said 1, as in Fig. 10, 95 thereby rendering the soap-frame easy of guidance and management.

We desire to lay particular stress upon the adjustment of Y, which we secure by simply turning the screw 13 in or out of the bearing 100 15 and maintaining our adjustment by means of the jam-nut 15', as much greater steering facility or much greater ease in the handling of a particularly heavy load may be secured by a simple adjustment of said 13. The advantage of this will be appreciated by those 105 who are called upon to handle any such weight in this manner.

The last point which we would mention is the manner in which we have strengthened 110 the iron sides 3. Instead of a large number of corrugations we have placed but a small number of entirely separate V-shaped or angular pieces 16 and fastened them in such a manner as to impart the greatest strength to 115 the structure.

As will be perceived by those skilled in the art, we have provided an invention whose main features are extreme simplicity in the action and manufacture of all parts, which 120 is possessed of efficiency in the fullest sense of the term, every part of which is possessed of every needful adjustment in case of wear or variance in circumstances, and that the effect of all our appliances, besides serving 125 their specified and allotted office, will be to strengthen and improve the efficiency of the entire frame, a particular instance of which is the manner in which the plate 6, situated upon the bottom of the platform 1 at each 130 end, which plate besides performing its allotted duty in its instrumentality in moving the frame forms an excellent and strengthening support for the parts A' and A³. We are un-

aware of any other manufacture of the class described having any of the characteristics of our invention. We further desire to say that we do not wish to be understood as limiting ourselves to the precise form of mechanism herein set forth nor to the same class of metal or material to be used in the various members of our invention as is herein stated.

Having thus described our invention, we claim and desire to secure by Letters Patent—

1. In a soap-frame the combination with the sides 3 and ends 2 of a soap-frame, of a rod 10 having an angular bend on one end extending inwardly over one of the sides 3 and said end being provided for the attachment of and in combination with an eccentric 9, the other end of said rod being straight and provided with a thread D², screwing into a threaded aperture provided in one end of another rod 11, said rod 11 having an angular bend similar to that provided on the rod 10, extending inwardly and embracing the other side 3 of the soap-frame, so devised that when the eccentric 9 is directed against the side 3 it will strain the angularly-bent rods 10 and 11 and cause a contraction of the parts against the sides 3 and thus hold same in rigid contiguity with the ends 2 as herein shown and described.

2. In a soap-frame the combination with the sections a', a², a³ of the platform of a soap-frame, of a plate bolted securely to the middle section on the under side thereof, provided with depressions E² into which fits a projecting, adjustable stud 13, located on the forward axle of said soap-frame, said axle being detachable and provided with wheels and a handle, so devised that the projecting stud 13, can be inserted into a suitable depression in the plate 6 and the depression of the handle of the soap-frame on the detachable axle will cause the projecting stud 13 to impinge against the plate 6 on the platform and cause one end of the frame to elevate; thus rendering it easier of manipulation as herein shown and described.

3. In a soap-frame the combination with the sides 3 and ends 2 of a soap-frame, of a rod 10 having an angular bend on one end extending inwardly over one of the sides 3 and said end being provided for the attachment of and in combination with an eccentric 9, the other end of said rod being straight and provided with a thread D², screwing into a threaded aperture provided in one end of another rod 11, said rod 11 having an angular bend similar to that provided on rod 10, extending inwardly and embracing the other side 3 of the soap-frame, so devised that when the eccentric 9 is directed against the side 3 it will strain the angularly-bent rods 10 and

11 and cause a contraction of the parts against the sides 3 and thus hold same in rigid contiguity with the ends 2, the mechanism being provided with a jam-nut for maintaining adjustment which is obtained by screwing the rod 10 into or out of the rod 11 as herein shown and described.

4. In a soap-frame the combination with the sections a', a², a³, of the platform of a soap-frame, of a plate bolted securely to the middle section on the under side thereof, provided with depressions E², into which fits a projecting, adjustable stud 13, located on the forward axle of said soap-frame, said axle being detachable and provided with wheels and a handle, so devised that the projecting stud 13, can be inserted into a suitable depression in the plate 6, and the depression of the handle of the soap-frame on the detachable axle, will cause the projecting stud 13 to impinge against the plate 6 on the platform and cause one end of the frame to elevate; thus rendering it easier of manipulation, and a suitable means for maintaining the adjustment of said projecting, adjustable stud as herein shown and described.

5. In a soap-frame the combination with the sides 3 and ends 2 of a soap-frame, of a rod having an angular bend extending over and embracing one of the sides 3, on one of the ends thereof, the other end extending across the end 2 of the soap-frame toward the other side 3, being straight and provided with a thread which screws into one end of a threaded coupling, said coupling having opposite threads and suitably flattened sides onto which a wrench may be applied; a rod similar to the first named extending similarly but oppositely across the end 2 toward the last-mentioned side 3, having an angular bend on one end extending over and embracing said side 3, the other end being straight and provided with a thread of the opposite cut to that mentioned on the first-named rod, which screws into said threaded coupling at the opposite end to said first-named rod so devised that the turning of the threaded coupling into which both angularly-bent rods are screwed will cause the rods to contract so that the bent portions will close in on the sides 3 and thus draw them into rigid contiguity with said ends 2 as herein shown and described.

In testimony whereof we have signed our names in the presence of the subscribing witnesses.

ERNEST A. HOUCHIN.
ANTHONY HUBER.
